(57) **CLAIM**

I claim, the ornamental design for a drinking glass assembly, as shown and described.

DESCRIPTION

FIG. 1 is a perspective view of a drinking glass assembly, showing my new design,

FIG. 2 is a side view thereof, all other sides being a mirror image hereof;

FIG. 3 is an exploded side view thereof, all other sides being a mirror image hereof; and,

FIG. 4 is a perspective view thereof.
